UNITED STATES PATENT OFFICE.

JOE G. GLADNEY, OF HOMER, LOUISIANA.

DESIGN FOR A POST-BASE.

SPECIFICATION forming part of Design No. 32,404, dated March 27, 1900.

Application filed February 27, 1900. Serial No. 6,760. Term of patent 7 years.

To all whom it may concern:

Be it known that I, JOE G. GLADNEY, a citizen of the United States, residing at Homer, in the parish of Claiborne and State of Louisiana, have invented and produced a new and original Design for a Post-Base, of which the following is a specification.

This invention relates to a new and original design for a post-base, and has for its object to provide a design of this character which shall be both ornamental and useful.

The leading feature of the present design resides in the substantially-straight and flat body and the pair of oppositely-spaced lateral projections located intermediate of the opposite ends of the body upon the same side and flush with the respective longitudinal edges thereof, said edges being converged upwardly from the projections and substantially parallel below the projections, the lower extremity of the body being in the form of a flat blade having the sharp laterally-convexed or outwardly-bowed lower edge.

Minor features of the design reside in the pair of vertically-aligned perforations in the upper portion of the body and above the projections, the flat upper faces of the projections, which faces extend at substantially right angles to the adjacent face of the body, the laterally-concaved inner faces of the projections, which merge into the adjacent face of the body, and the laterally-beveled outer edges of the lower portions of the projections, said beveled edges also merging into the body adjacent to the lower end thereof, the rear or outer face of the body being free from projections and the lower portion thereof being beveled or inclined inwardly and downwardly to the lower edge thereof.

In the drawings, Figure 1 is a perspective view of a post-base embodying the present design. Fig. 2 is an edge elevation thereof. Fig. 3 is a transverse sectional view taken on the line 3 3 of Fig. 2.

Corresponding parts in the several figures

of the drawings are designated by like characters of reference.

Referring to the accompanying drawings, the numeral 1 designates the substantially-straight and flat body of the base, which has 50 the pair of oppositely-spaced lateral projections 2, which are located intermediate of the opposite ends of the body. The upper faces 3 of the projections extend at substantially right angles to the body, and the outer faces 55 4 are flush with the respective longitudinal edges of the body. Each projection is provided with a laterally-concaved face 5, which merges into the adjacent inner face of the body. The lower portions of the outer edges 60 of the projections are beveled laterally, as indicated at 6, and these beveled edges incline inwardly and downwardly and also merge into the inner or front face of the body adjacent to the lower end thereof. The opposite 65 longitudinal edges of the body converge upwardly from the projections, as indicated at 7, and the lower portions of said edges are substantially parallel. A pair of vertically-aligned perforations 8 are located in the upper 70 portion of the body and above the projections. The lower extremity of the body is in the form of a flat blade 9, having the sharp lower edge 10, which is convexed or bowed laterally. The outer or rear face 11 of the body is free 75 from projections, and the lower portion thereof is beveled or inclined inwardly and downwardly to the lower edge 10, as indicated at 12.

What I claim is—

The design for a post-base, as herein shown and described.

In testimony that I claim the foregoing as my own I have hereto affixed my signature in the presence of two witnesses.

JOE G. GLADNEY.
